UNITED STATES PATENT OFFICE.

GEORGE J. OLTSCH, OF SOUTH BEND, INDIANA.

PACKAGE.

Application filed August 18, 1924. Serial No. 732,620.

The invention relates to special packages, and has for its object to provide means whereby an article to be displayed on a card easel may be shipped and stored in the 5 chamber of a box disposed with a plurality of boxes having similar articles within a large box, whereby it will not be necessary to ship the easel and articles secured thereto, separately to a merchant, and at the 10 same time utilize one of the articles for display purposes without the necessity of furnishing the article free of charge as an extra one. The device is particularly adapted for use in connection with fish baits, however 15 it is applicable in connection with other articles.

A further object is to provide an easel within the upper end of a box between the lid thereof and a plurality of boxes in the 20 chamber of the box, and an article on said easel, positioned whereby, when the easel is in position, said article will be disposed in the chamber of one of the plurality of boxes, said easel also forming means for maintaining 25 the article carried thereby spaced from the walls of the box in which it is disposed, thereby preventing rattling of the article during shipment, or damage thereto.

With the above and other objects in view 30 the invention resides in the combination and arrangement of parts as hereinafter set forth, shown in the drawing, described and claimed, it being understood that changes in the precise embodiment of the invention 35 may be made within the scope of what is claimed without departing from the spirit of the invention.

In the drawings:—

Figure 1 is a perspective view of the pack- 40 age, showing the easel in position on top of the plurality of boxes and the cover of the main box removed.

Figure 2 is a perspective view of the main 45 box with a plurality of boxes therein and showing the article receiving box open.

Figure 3 is a vertical longitudinal sec- 50 tional view through the main box, showing the easel card in position with the article carried thereby disposed in the open small box.

Figure 4 is a perspective view of the easel 55 card, showing the article attached thereto.

Referring to the drawings, the numeral 1 designates the main box or container, in the 55 chamber 2 of which is disposed a plurality of small boxes 3, twelve of which are shown

for purposes of illustration, and in which boxes articles to be vended are disposed in the usual manner. It has been found, especially in the sale of fish bait, it is necessary to furnish the merchants with a bait attached to a display card 4 for display purposes, however it has been the practice to furnish the bait as an extra bait and free of charge, consequently it involved charging more for the box of bait, or a loss to the manufacturer. To obviate the above difficulty, which not only involved expense, but an additional expense in shipping the display card with the bait 5 thereon in a separate box. The method of packing herein-after set forth is designed. The boxes 3 are arranged within the main box 1 in the usual manner as clearly shown in Figures 2 and 3, however one of the boxes 3 in the upper layer is open with its cover 6 on the bottom thereof, therefore it will be seen that the chamber 7 is open, and in a position whereby, when the card 4 is turned upside down on the top layer of the boxes, the bait 5, which is secured thereto at 8, will be received within the chamber and the easel card interposed between the upper layer of small boxes 3 and a cover 9 of the main box 1, and a relatively small amount of additional space is required and the bait 5 is disposed in a box, in which it may be placed for sale after the bait in the other boxes 3 have been vended, consequently it is not necessary to furnish a merchant with an extra bait free of charge for display purposes, or cover the extra bait by an increased price of baits. The easel card 4 is provided with spaces 10 and 11, on which

any suitable advertising matter may be 95 printed, for instance the trade-mark of the goods, name of the country or any other subject matter. It is also provided with a hinged leg 12 for supporting the same in an inclined position on the counter. Card 4 is 100 preferably of a size whereby it will cooperate with the walls of the main box 1 for maintaining the bait 5 or other article secured thereto in spaced relation to the walls of the chamber of the box, consequently it 105 will not have freedom of movement within the box and can not become damaged or marred during shipping. It is obvious that the bait 5 may be attached to the easel card 1 in various positions, so that it can be 110 received within any of the small boxes 3 of the upper layer of boxes, and it does not

necessarily have to be in the particular box 3 shown in the drawing.

From the above it will be seen that means is provided whereby an article carried by a 5 display card may be stored within a main box having a plurality of boxes therein, in a manner whereby the additional room required in the main box is reduced to a minimum and the article received in the chamber of one of the plurality of boxes, and in 10 which last named box the article may be placed and vended after the other articles have been sold. It will also be seen that the 15 necessity of supplying the merchant with an extra article for display purposes is obviated.

The invention having been set forth what is claimed as new and useful is:—

1. The combination with a large box, of 20 a plurality of small boxes disposed therein, covers on said small boxes, one of said small boxes being open, a cover for the large box,

a display card disposed within the large box between the cover thereof and the plurality of small boxes, and an article carried 25 by the display card and disposed in the chamber of the open small box.

2. The combination with a large box, of a plurality of small boxes disposed therein and having articles therein, covers carried 30 by the small boxes, one of said small boxes being open and empty, a cover for the large box, a display card disposed within the large box between the cover and the plurality of small boxes, an article carried by 35 the display card and disposed in the chamber of the open small box, said display card cooperating with the walls of the box and forming means for maintaining the article carried by the card in spaced relation to 40 the walls of the open small box.

In testimony whereof I affix my signature.

GEORGE J. OLTSCH.
